SCREEN AND LINER SETTING, SETTING TOOL AND WASH PIPE

Theodore W. Munhausen, Houston, Tex., assignor to Leslie A. Layne, Houston, Tex.

Application September 2, 1953, Serial No. 378,113

3 Claims. (Cl. 166—144)

The invention concerns means for completing wells. It concerns more particularly certain specific improvements in a well known combination which comprises a screen and liner setting, a setting tool and a wash pipe.

In completing wells, it is customary to lower into the well, after casing has been set, a screen and liner setting comprising a set shoe, a screen, a liner and a collapsible packer, which are connected and disposed one above the other. The screen and liner setting is lowered into the well on a string of tubing having a setting tool removably connected to its lower end. The setting tool is removably connected to the screen and liner setting, whereby it may be disengaged therefrom, leaving the screen and liner setting in the well. The setting tool includes means for collapsing the packer, and this is accomplished by causing the setting tool to bear upon the collapsible portion of the packer in such a way that the weight of the setting tool and the supporting tubing causes the packer to collapse. A wash pipe, which is carried by the setting tool, is disposed within the screen and liner setting and forms an imperforate conduit extending downwardly thru the screen.

A conventional type of packer, in which the stem is receivable telescopically within the lower end of the packer barrel and extends downwardly therefrom, and in which the packer is collapsed by causing the weight of the supporting tubing to bear upon the packer barrel, forcing it downwardly over the stem, is illustrated in U. S. Patent No. 1,870,779, dated August 9, 1932, issued to Leslie A. Layne and Albert L. Roco.

A disadvantageous feature of the conventional type of packer, above referred to, is that the weight of the supporting tubing is not always sufficient to fully collapse the packer. This is particularly true in shallow wells. The collapsible canvas portion of the packer begins to fold outwardly from the top, and immediately the folds of canvas engage the casing. The friction between the canvas and the casing, as well as the pressure of well fluids on the under side of the packer, must be overcome in order to fully collapse the packer.

An improved arrangement, in which the packer is disposed upside down, and the stem is receivable telescopically within the upper end of the packer barrel and extends upwardly therefrom, and in which the packer is collapsed by causing the weight of the supporting tubing to bear upon the packer stem, forcing it downwardly in the barrel, is illustrated in U. S. Patent No. 2,243,967, dated June 3, 1941, issued to Leslie A. Layne, Harold C. Block and Albert L. Roco. In this type of arrangement the collapsible canvas portion of the packer begins to fold outwardly from the bottom, and there is no resistance to the downward movement of the packer stem caused by friction between the folds of canvas and the casing.

The present invention is an improvement over the arrangement shown in the patent of Leslie A. Layne, Harold C. Block and Albert L. Roco, No. 2,243,967, above referred to, and is intended particularly for use in an operation such as that described in a copending application of Leslie A. Layne, Serial No. 343,916, filed March 23,

2

1953, which concerns a method of gravel packing wells in which gravel is deposited in an under-reamed portion of a well bore, after casing has been set, and thereafter a screen and liner setting is lowered to the bottom of the well, thru the gravel deposit, while circulating fluid into the well, thru a wash pipe disposed within the screen and liner setting, to displace the gravel ahead of the screen and liner setting.

In the gravel packing operation described in the copending application of Leslie A. Layne, Serial No. 343,916, it is desirable to employ an upside down packer of the type shown in the patent of Leslie A. Layne, Harold C. Block and Albert L. Roco, No. 2,243,967, for the reasons stated. It is also desirable to employ a packer which is of relatively small diameter, whereby a cutting tool may be moved downwardly over the packer, in the annulus between the packer barrel and the casing, to cut away the canvas portion of the packer whereby the screen and liner setting may be removed from the well after the packer has been collapsed. In order to compensate for the small diameter of the packer, it is desirable to use an arrangement of the type described in U. S. Patent No. 2,082,113, dated June 1, 1937, issued to Leslie A. Layne and Louis C. Mundt, in which the effective diameter of the packer, upon collapsing it, is increased by slotting the canvas portion thereof.

A disadvantageous feature of the arrangement shown in the patent of Leslie A. Layne, Harold C. Block and Albert L. Roco, No. 2,243,967, is that the supporting tubing, which serves also as the wash pipe, is connected to the screen and liner setting at the set shoe. The wash pipe necessarily is of relatively small diameter, and extends downwardly thru the liner, which may be from about 40 feet to about 200 feet long, for example. It is sometimes difficult to connect the wash pipe to the set shoe, after it has been disengaged therefrom, to remove the screen and liner setting from the well.

The present invention contemplates connecting the supporting tubing to the screen and liner setting above the liner, adjacent the lower end of the packer barrel. This reduces the length of the supporting tubing, which may be of somewhat larger diameter than the wash pipe, and facilitates connecting the tubing to the screen and liner setting after it has been disengaged therefrom.

Another disadvantageous feature of the arrangement shown in the patent next above referred to is that the supporting tubing, which serves also as the wash pipe, must be accurately measured and cut in order for the setting tool to function properly.

Applicant's invention contemplates an improved arrangement in which the wash pipe is suspended from the supporting tubing and is freely movable with respect thereto. The wash pipe is not connected to the screen and liner setting.

Applicant's invention also includes improved means carried by the packer stem for effecting a seal between the supporting tubing and the packer.

The invention will be readily understood by referring to the following description and the accompanying drawing, in which:

Fig. 1 is a diagrammatic view in elevation showing the apparatus of the invention disposed in a well bore, before collapsing the packer.

Fig. 2 is a diagrammatic view in elevation showing the apparatus after the packer has been collapsed and the setting tool has been disengaged from the screen and liner setting.

Figs. 3, 3A, 3B and 3C together constitute a single view, which is an enlarged view in elevation, partly in section, of the apparatus shown in Figs. 1 and 2.

Referring to the drawing, the numeral 1 designates a well bore. The well bore 1 has been under-reamed, and

gravel has been deposited in the under-reamed portion. A string of casing, indicated by the numeral 2, has been set in the well bore 1, and a screen and liner setting as hereinafter described has been lowered into the well.

The screen and liner setting comprises a set shoe 3, a screen 4, a liner 5 and a collapsible packer 6, which are connected and disposed one above the other. The liner 5 consists of an imperforate pipe, which may be from about 40 feet to about 200 feet long, for example, and is provided with centering guides 5a for engagement with the casing 2. In its expanded position the packer 6 engages the casing 2 whereby a seal is formed between the casing 2 and the screen and liner setting, and fluids entering the well from the producing formation are caused to flow thru the screen 4.

The screen and liner setting is lowered into the well on a string of tubing 7 having a setting tool 8 removably connected to its lower end. The setting tool 8 is removably connected to the screen and liner setting, as hereinafter described, whereby it may be disengaged therefrom, leaving the screen and liner setting in the well.

The setting tool 8 includes means for collapsing the packer 6, as hereinafter described. This is accomplished by causing the setting tool 8 to bear upon the collapsible portion of the packer 6 in such a way that the weight of the setting tool 8 and the supporting tubing 7 causes the packer 6 to collapse.

A wash pipe 9, which is carried by the setting tool 8, as hereinafter described, is disposed within the screen and liner setting. The wash pipe 9 is freely movable with respect to the tubing 7 and the setting tool 8, and is acted upon by the pressure of circulating fluid moving downwardly thru the tubing 7 to cause its lower end to engage a seat 10 provided therefor in the set shoe 3. The seat 10 is formed in the upper end of an upstanding tubular member 10a, which is disposed concentrically within the set shoe 3 and has a flanged lower end connected to the inner wall thereof. Thus the wash pipe 9 forms an imperforate conduit extending downwardly thru the screen 4. A pair of spring biased back pressure valves 11, which are disposed one above the other within the set shoe 3, below the seat 10, permit fluid to be discharged thru the wash pipe 9 and the set shoe 3 while preventing the flow of well fluids in reverse direction.

The packer 6 comprises a barrel 12, which is connected to the upper end of the liner 5 by a swaged nipple 13, and a stem 14 which is receivable telescopically within the barrel 12. Before the packer 6 is collapsed the stem 14 extends upwardly above the barrel 12, and only the lower end of the stem 14 is received within the barrel 12. The upper end of the stem 14 is removably connected to the lower end of a coupling 15, as hereinafter described. The upper end of the coupling 15 is connected by left-hand threads 15a to a stuffing box 16, which forms a seal between the coupling 15 and the tubing 7.

In its extended position, the stem 14 of the packer 6, above referred to, is enclosed within a collapsible tube 17, which is formed of several layers of spirally wrapped canvas and is anchored at its ends to the barrel 12 and the stem 14. The arrangement is such that, upon telescoping the stem 14 within the barrel 12, the canvas tube 17 is collapsed like a bellows and forms a seal between the barrel 12 and the stem 14, which with the canvas tube 17 comprise the packer 6, as above described, and the casing 2.

The canvas tube 17 advantageously may be slotted as described in the patent of Leslie A. Layne and Louis C. Mundt, No. 2,082,113, above referred to, whereby its effective diameter, when collapsed, may be increased.

Ratchet type threads 20 are formed on the outer surface of the stem 14 for engagement by corresponding threads 21 which extend inwardly from a longitudinally slotted portion of the barrel 12. The threads 20 and 21 retain the packer 6 in its collapsed position. The threads 20 are not necessarily continuous, but may be separated by

an unthreaded intermediate portion 14a of the stem 14, which slidably engages a corresponding unthreaded portion which comprises the extreme upper end 12a of the barrel 12. The upper end 12a of the barrel 12 may be tapered externally whereby it may be readily forced between the stem 14 and the canvas tube 17.

The ends of the swaged nipple 13 are connected to the upper end of the liner 5 and the lower end of the packer barrel 12. An intermediate portion of the swaged nipple 13 is threaded internally at 13a, with left-hand threads, for engagement by a tubular fitting 23, which is removably connected to the lower end of the setting tool 8, as hereinafter described.

The lower end of the tubular fitting 23 slidably engages 15 the wash pipe 9 at 23a, and serves as a centering guide therefor. An internal shoulder 24, which is formed in the tubular fitting 23, is adapted to engage the wash pipe 9, as hereinafter described, whereby the wash pipe 9 may be lifted.

The setting tool 8, which is disposed initially within the packer 6, below the coupling 15 and the stuffing box 16, is removably connected to the lower end of the tubing 7 and to the tubular fitting 23. As shown, the setting tool 8 is connected to the tubular fitting 23 by a nipple 25 and a coupling 26. The nipple 25 actually is a downward extension of the setting tool 8, and is required only when the diameter of the packer barrel 12 is relatively small. The lower end of the setting tool 8 may be connected directly to the tubular fitting 23 when the diameter of the packer barrel 12 is sufficiently large to provide the necessary space.

The wash pipe 9 is freely movable within the tubing 7, the setting tool 8 and the nipple 25, and the lower end thereof is maintained in engagement with the seat 10 by 35 the action of washing fluid moving downwardly thru the tubing 7 on a tubular piston 27, which is connected to the upper end of the wash pipe 9 and forms a seal between the wash pipe 9 and the tubing 7. An external shoulder 27a formed by the lower end of the piston 27 is adapted to engage the internal shoulder 24 of the tubular fitting 23, whereby the wash pipe 9 may be lifted.

The setting tool 8 includes means for collapsing the packer 6, as hereinafter described. The setting tool 8 has a tubular body 28 which is connected at its ends to the tubing 7 and the coupling 26, or alternatively, the tubular fitting 23, as above described. An annular groove (not shown) is formed in the peripheral surface of the tubular body 28, and a pair of semi-circular dogs 30 are disposed within the groove. The dogs 30 are acted upon by a plurality of coil springs 31, which are disposed between them, whereby they are urged outwardly in opposite directions. A circular band 32, which is attached to the tubular body 28, loosely retains the dogs 30 in engagement with the tubular body 28 while permitting them to be expanded by the action of the springs 31.

In collapsing the packer 6, the setting tool 8 is first disengaged from the screen and liner setting, by rotating the tubing 7 whereby the tubular fitting 23 is disengaged from the swaged nipple 13. The setting tool 8 is then lifted 60 until the expandable dogs 30 are in engagement with an annular groove 34, which is formed in the inner surface of the packer stem coupling 15 below the stuffing box 16. An internal shoulder 35, which is formed in the coupling 15 below the groove 34, engages external shoulders which are formed by the lower edges of the dogs 30, whereby the weight of the entire string of tubing 7 is caused to bear upon the packer stem 14, causing it to telescope within the packer barrel 12 and collapse the canvas tube 17.

A pair of diametrically opposed lugs 36 extend upwardly from the upper edge of the setting tool 8 for engagement with corresponding slots 37 formed in the lower edge of the stuffing box 16, whereby the stuffing box 16 may be disengaged from the packer stem coupling 15 by lifting 70 the setting tool 8 until the lugs 36 engage the slots 37,

and then rotating the stuffing box 16 with respect to the packer stem coupling 15.

In operation, the screen and liner setting, comprising the set shoe 3, the screen 4, the liner 5 and the packer 6, is first lowered into the well on the tubing 7 and the setting tool 8, and washing fluid is circulated downwardly into the formation thru the tubing 7, the wash pipe 9 and the set shoe 3. Thereafter the setting tool 8 is disengaged from the screen and liner setting, by rotating the tubular fitting 23 with respect to the swaged nipple 13, and the setting tool 8 is lifted until the wash pipe 9 is disengaged from the seat 10. Washing fluid is then directed upwardly inside the screen and liner setting. The setting tool 8 is then lifted further until the expansible dogs 30 of the setting tool 8 are in engagement with the annular groove 34 of the packer stem coupling 15. The setting tool 8 is then lowered whereby the weight of the entire string of tubing 7 is caused to bear upon the packer stem 14, and the stem 14 telescopes within the packer barrel 12, causing the canvas tube 17 to collapse. The setting tool 8 is then lifted whereby the lugs 36 of the setting tool 8 engage the slots 37 of the stuffing box 16, and the stuffing box 16 is rotated whereby it is disengaged from the packer stem coupling 15.

The invention may be modified in various ways without departing from the spirit and scope thereof.

I claim:

1. In combination, a screen and liner setting comprising a set shoe, a screen, a liner and a collapsible packer disposed one above the other and connected end to end, the packer including a barrel connected at its lower end to the upper end of the liner, a stem receivable telescopically within the barrel and extending upwardly therefrom, and a canvas tube surrounding the stem and connected at its ends to the stem and the barrel, respectively, a coupling connected at its lower end to the upper end of the stem and having an annular groove formed in the inner wall thereof, a string of tubing, a setting tool connected to the lower end of the tubing and received within the stem, below the annular groove of the coupling, the setting tool having a plurality of spring biased expansible dogs receivable in the annular groove of the coupling whereby the weight of the string of tubing may be caused to bear upon the stem to expand the packer, a pipe comprising a downward extension of the setting tool and extending downwardly thru the packer, coupling means comprising a downward extension of the packer barrel and connecting the lower end of the packer barrel to the upper end of the liner, a tubular fitting connected at its upper end to the lower end of the pipe and connected by left-hand threads to the coupling means, and a wash pipe disposed within the tubing and freely movable longitudinally with respect thereto, the lower end of the wash pipe en-

gaging a seat provided therefor in the set shoe and the upper end of the wash pipe carrying a tubular piston, the tubular fitting slidably engaging the wash pipe and having an internal shoulder for engagement by an external shoulder formed by the under side of the tubular piston.

2. In apparatus as described in claim 1, a stuffing box surrounding the tubing and connected by left-hand threads to the coupling, and mutually engaging means carried by the stuffing box and the setting tool, respectively, whereby the stuffing box may be disengaged from the coupling by rotating the setting tool.

3. In combination, a screen and liner setting comprising a set shoe, a screen, a liner and a collapsible packer disposed one above the other and connected end to end, the packer including a barrel connected at its lower end to the upper end of the liner, a stem receivable telescopically within the barrel and extending upwardly therefrom, and a canvas tube surrounding the stem and connected at its ends to the stem and the barrel, respectively, whereby the canvas tube may be expanded by telescoping the stem with respect to the barrel, a coupling connected at its lower end to the upper end of the stem and having an annular groove formed in the inner wall thereof, a string of tubing, a setting tool connected to the lower end of the tubing and received within the stem, below the annular groove of the coupling, the setting tool having a plurality of spring biased expansible dogs receivable in the annular groove of the coupling whereby the weight of the string of tubing may be caused to bear upon the stem to expand the packer, a pipe nipple connected to the lower end of the setting tool and extending downwardly thru the packer, a coupling connected at its ends to the lower end of the packer barrel and the upper end of the liner, a tubular fitting connected at its upper end to the lower end of the nipple and connected by left-hand threads to an intermediate portion of the last mentioned coupling, and a wash pipe disposed within the tubing and freely movable longitudinally with respect thereto, the lower end of the wash pipe engaging a seat provided therefor in the set shoe and the upper end of the wash pipe carrying a tubular piston forming a seal between the wash pipe and the tubing, the tubular fitting slidably engaging the wash pipe and acting as a centering guide therefor, and the tubular fitting having an internal shoulder for engagement by an external shoulder formed by the under side of the tubular piston whereby the wash pipe may be suspended from the tubing.
